CLAIM

The ornamental design for a sport towel having multiple sealable pockets and a lower open flap, as shown and described.

DESCRIPTION

FIG. 1 is a front elevational view of a sport towel having multiple sealable pockets and a lower open flap showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The horizontal and vertical broken lines shown in FIGS. 1 and 2 indicate stitching.
